GUEST ANNOUNCER

James W. Brown, Los Angeles, Calif., assignor to
Carl O. Nordensson, Buffalo, N. Y.

Application May 25, 1931, Serial No. 539,787

2 Claims. (Cl. 177—7)

My invention relates to improvements in what I have chosen to term a "guest announcer", the primary object being to provide simple and effective means for sounding in a more pleasing manner the arrival of a caller at the entrance of a dwelling or other place. A further object is the provision of a device of the class stated which is less expensive in construction than heretofore, thus tending to popularize a device which produces more pleasing effects. Further objects will be apparent from the following description.

To these ends my invention comprises the features of construction and combination of parts hereinafter described and claimed.

In the accompanying drawing forming part of this specification, Fig. 1 is a front elevation of my invention, part of the structure being broken away and in section and the electric circuit being indicated diagrammatically, and Fig. 2 is a side elevation of the structure shown in Fig. 1, part of the structure also being broken away and the electrical circuit not shown.

In the drawing A indicates a suitable base or back upon which the parts of my improved structure are mounted and B a suitable cover which may be ornamented as desired so as to produce an attractive configuration suitable for use in any dwelling or place, said structure being adapted to be fastened on the wall or otherwise stationed within hearing range of the occupants to announce the arrival of a guest or other person at an entrance. In this structure is arranged a suitable sounding device which as shown consists of a pair or plurality of chime rods 10 and 11, disposed vertically or otherwise at either side of the structure and rigidly secured respectively to the metallic head pieces 12 and 13, which are mounted at the upper end of the base A, by screws 14 or other suitable means. These chime rods 10 and 11 are of different lengths, each of them imparting a different musical note when set in vibration by a striker to be hereinafter described.

Arranged within the structure on a pinion or shaft 15 is a pendulum C, which is so balanced as to have a fairly long period of oscillation, the counter weights 16 and 17 on its upper and lower ends serving to augment this action and impart momentum thereto.

Attached to opposite sides of the pendulum C below the pinion 15 are two spring switch arms 18 and 19, carrying suitable contact points 20 designed to make contact with suitable adjustable screw contacts 21 and 22 when the pendulum swings to either side of its normal position. Also suitably attached to one side of the pendulum

above said pinion is an armature 23. In juxtaposition to said armature and secured rigidly to said base A is an electro magnet D which when energized serves to attract the armature 23 and draw the pendulum C over against stop pins 24 and 25, on the base, and hold it in said position as long as said electro magnet remains energized.

An electric circuit E, containing a spring switch 26, adapted to be located at the entrance of a dwelling or in any other desired position, and receiving current from any suitable source such as 27, located at any desired distance from the device, contains the winding of the electro magnet D so as to energize the electro magnet when and as long as the switch remains closed. The switch 26 may be of the usual push button or any other type and the source of current may be the usual bell transformer receiving current from any power circuit. The circuit E is wired into the device through terminals 28 and 29.

The winding of the electro magnet D is in series with the winding of a solenoid F, in circuit E, which when energized draws up the plunger core 30, separating the contact of the core 30 with a stationary contact terminal 31, and serving to open a branch circuit G, normally passing through the solenoid core 30, flexible conductor 32 connected with the solenoid core and a fixed binding post 33 which is connected with circuit E.

The striker consists of a solenoid H having two windings 35 and 36 containing a leather tipped core 37, which is free to play backward and forward through the solenoid, being disposed so as to alternately strike the chime rods 10 and 11, when windings 35 and 36 are alternately energized. One end of each of the coils 35 and 36 is connected with one side of the circuit E by the conductor 38 traversing a third terminal 39 on the base. The opposite end of coil 35 is connected by the conductor 40 with the pendulum contact 21 while the opposite end of coil 36 is connected by conductor 41 with the opposite pendulum contact 22.

In operation, when the circuit E is closed by the switch 26, current energizes electromagnet D and solenoid F, said magnet attracting armature 23 and holding the pendulum in energized position against the stops 24 and 25 while the switch remains closed and said solenoid opening the branch circuit G by raising the solenoid core 30 from contact with terminal 31. When the switch 26 is released, that is opened, both electro magnet D and solenoid F are deenergized, the pendulum C is released and the core 30 closes branch circuit G through contact 31. With this

action the pendulum oscillates freely backward and forward over a fairly long period, making at each stroke first contact with terminal 22 and then terminal 21 successively. Inasmuch as the 5 branch circuit G is closed through solenoid core 30 and terminal 31, current is caused to pass first through solenoid coil 36 and then solenoid coil 35 successively, thus causing the striker solenoid core to oscillate and impinge against first the sounding 10 rod 11 and then the sounding rod 10. This action transpires automatically until the stroke of the pendulum is so reduced as to fail to make connection between the spring contact elements 18 and 19 and the terminals 21 and 22. The length 15 of period during which the sounding rods are successively struck by the striker core 31 may be varied through the adjustment of the screws 21 and 22. When the pendulum is released from magnet D, by opening of main circuit E, the coil 20 36 of solenoid H is energized and the striker core 31 plunges towards sounding rod 11. The momentum of the striker core carries it beyond the point of maximum flux density of solenoid 36 so that it strikes sounding rod 11, sounding a musical note. After striking, the plunger 37 rebounds 25 to the position of maximum flux density of solenoid coil 36 and is held in the latter position clear of the vibrating rod 11. Pendulum C then swings the opposite way, closing contacts 20 and 21, allowing current to traverse the solenoid coil 35, 30 causing plunger 37 to strike sounding rod 10 in the same manner. This alternate striking of the sounding rods continues in synchronism with the beat of the pendulum until the latter approaches 35 at rest position, the number of strokes of the chime sounding being determined by contacts 21 and 22 which are adjusted so that sounding rod 10 will be the last note sounded, thus leaving the striker plunger 37 in readiness for future operation. The stop pins 24 and 25 prevent the armature 23 from making contact with the pole of magnet D, which with alternating current would 40 cause a buzzing noise at this point.

The purpose of solenoid F is to allow the operation of the apparatus on a smaller transformer 45 than would be otherwise possible. The ordinary door bell transformer has a very limited current output and is incapable of operating both electromagnet D and solenoid H at the same time. When contacts 20 and 21 are closed as 50 pendulum C swings in response to electromagnet D, the flow of current through the solenoid coil 35 would so weaken magnet D that said pendulum would tend to fall back into median position. As 55 soon as contacts 20 and 21 are opened the pendulum is fully attracted and thus would move back and forth on one side of median position as long as the switch 26 is closed. Solenoid F prevents this action by opening the circuit to 60 solenoid H, the instant switch 26 is closed so that pendulum C is held in raised or superior position against stop pins 24 and 25 until switch 26 is released or opened.

In accordance with the patent statutes, I have described the principles of operation of my invention, together with the apparatus which I now consider to represent the best embodiment thereof but I desire to have it understood that the 5 construction shown is only illustrative and that the invention can be carried out by other means and applied to uses other than those above set forth within the scope of the following claims.

Having described my invention, what I claim 10 as new and desire to secure by Letters Patent is:

1. A sound producing device, comprising, in combination, a base member, a supporting member on said base member, a sounding rod suspended from each of the opposite ends of said 15 supporting member, solenoid windings below said supporting member extending horizontally between said sounding rods and having substantially aligned axes, a solenoid core freely reciprocable and of such length relative to said windings 20 as to be moved to one extreme position and strike one of said rods when only one winding is energized and to the other extreme position and strike the other of said rods when only the other winding is energized, a pendulum hung on said 25 base member below said windings, a two way switch connected with said windings and actuated by the swinging movement of the pendulum to direct current alternately through said windings and cause said core to reciprocate, an electro 30 magnet having an actuating coil and armature associated with the pendulum below said solenoid windings and a switch controlled electric circuit connected with the coil of said electromagnet by which said coil is energized and the pendulum 35 set in free swinging motion.

2. A sound producing device, comprising, in combination, a base having supporting means extending transversely thereof, sounding elements carried by the opposite end portions of said supporting means, striking means between said sounding elements comprising adjacently disposed solenoids having windings extending toward said sounding elements, a sounding rod striking core movable through said solenoid windings and of 45 such length relative to said windings as to be moved to one extreme striking position only when one winding is energized and to the other extreme striking position when the other winding is energized, a pendulum poised on said base and associated with said windings, a source of electrical 50 current, switching means connected with said windings and source of current, said switching means being associated with and actuated by the swinging movement of the pendulum to direct energizing current alternately through said windings and cause said core to reciprocate, and switch controlled means in proximity to the pendulum 55 and connected with said source of current for 60 imparting swinging motion to the pendulum.

JAMES W. BROWN.
